FOLDER CONTROL WITH TIMER SELECTOR

Benjamin Alvin Buss, East Moline, Ill., assignor to American Machine and Metals, Inc., New York, N. Y., a corporation of Delaware

Application November 6, 1953, Serial No. 390,587

4 Claims. (Cl. 270—81)

The present invention relates broadly to automatic control mechanism and more particularly to a sensitive measuring device for controlling the various lines of folds in laundered articles which are folded after being ironed.

In the laundry machine art there has been more and more demand for automatic machinery to perform operations more rapidly than possible when performed by human hands. Accordingly, the speeds of delivery of ironing machines and folding machines has increased to the point where articles to be folded pass through a folder at speeds in excess of one hundred feet per minute. Such speeds have made the problem of accurately measuring and folding an article more difficult. The time lags involved in ordinary relays, for instance, is such that errors in the folding line of several inches may be encountered because of the time it takes for such devices to operate in their movement of pulling in and dropping out.

In order to eliminate as many time lags as possible I have caused rapid action switches to be operated directly by the power exerted upon measuring fingers or the like as an article to be folded passes a given point in the conveyor tapes of a folding machine. Accordingly, I encounter only one time lag which is that of the acceleration of the mass of the parts of the measuring device. By keeping the mass as low as possible within sound engineering technique and employing as substantial a spring force as can be operated by the articles, it is possible to reduce this time to a very small fraction of a second. Hence, in practicing my invention, it becomes possible to fold sheets and the like almost as accurately as can be done by hand but at several times the speed that such operations can be performed by hand.

Accordingly, a prime object of my invention is to provide an improved measuring device for folding machines or the like which receive articles of varying length and folds them into a predetermined number of folds.

In another aspect of the invention, an arrangement has been provided particularly useful with the sensing device of the present invention and wherein a plurality of timing means is employed having two characteristic manners of operation, such as two speeds. The particular timing means to be operated is controlled by a selector means, the selector means being operated or turned by a control means. The control means, which includes a rotatable ratchet wheel, is operated by a sensing device having two positions. When the sensing means is in a first position in response to a passing article, the appropriate selector unit will start one of said timers in its first characteristic manner, the control means having been rotated by movement of the sensing units. When the sensing unit is moved to its second position after passage of said article, the control means or ratchet wheel will be moved in the same direction thereby. Upon movement of the selector device in response to movement of the sensing means to said second position the timing means will be caused to operate in its second characteristic manner.

Other objects and advantages of my invention reside in the details of construction and the arrangement of parts

2

to be more fully described below, set forth in appended claims and shown in the accompanying drawings in which:

Fig. 1 is a diagrammatic view of a folding machine,

Fig. 2 is a semi-detailed semi-diagrammatic view of the measuring switch portion of my invention,

Fig. 3 is a semi-detailed semi-diagrammatic view of a timer shown more in detail in the application of Benjamin S. Kagan S. N. 312,834, now Patent No. 2,774,592, and,

Fig. 4 is a partial view similar to Fig. 2 but showing the parts in a different position such as occurs when a sheet or the like is not in engagement with the measuring finger thereof.

Referring more in detail to the drawing and first to Fig. 1, a folding machine generally indicated at 10 is

15 adapted to receive sheets 11, 12, 13 and 14 in succession from an ironing machine, not shown. Sets of conveyor tapes 15, 16, and 17 deliver these sheets progressively through the machine until finally folded sheets or the like are delivered to a receiving table 18. The rolls carrying the tapes 15, 16 and 17 are suitably power driven by drive means, not shown.

20 As shown in the drawing, the sheet 12 is passing a measuring finger 20 which was in the position shown in Fig. 2 during the passage of the sheet. The measuring finger 20 operates controls within a case 21 to set up operation of timing mechanisms within a case 22 to operate folding blades 23 and 24 when the sheet 12 attains the proper position in the folding machine 10. As the sheet passes through the machine and reaches the proper position, first 25 the blade 23 is operated by an electric motor 25 or the like under the influence of the timers in the control box 22. Similarly when the sheet advances adjacent the folding blade 24 a motor 26 or the like operates same to cause a second fold under the influence of the controller in the 30 control box 22, all to be described more in detail below.

35 Referring to Figs. 2 and 3 the measuring finger 20 is shown in a position which it would take just during passage of an article. When the sheet 12 is between the conveyor tapes 15, and the leading edge of a sheet 12 or the like engages the finger in its dotted line position, the finger will be rotated clockwise into the position shown in full lines. By such rotation a ratchet 30 is caused to move $\frac{1}{16}$ of a turn to the position shown in Fig. 2. In this position a roller on a switch arm 31 will be forced by a spring 31a into a dwell 32 of a cam 33 and close a contact 34. The spring 31a by forcing the roller into the dwell 32 contributes to proper and accurate operation of the mechanism. Cams 35, 36 and 37 are all similar to cam 33 having two dwells 180 degrees apart but spaced successively 40 radially by forty-five degrees. Thus for every $\frac{1}{8}$ turn of the ratchet 30 the rollers of switches 31, 38, 39 and 40 successively drop into their respective dwells and only one at a time will do so. Thus, as the finger 20 moves to the advanced position shown in Fig. 2 and thereafter 45 back to the retracted position shown in Fig. 4, the ratchet 30 will be advanced by the two said motions by $\frac{1}{8}$ of a turn (or forty-five degrees) in two $\frac{1}{16}$ turn increments.

50 The details of construction of my improved ratchet mechanism will now be described. The ratchet 30 is mounted on suitable bearings, not shown, in a box 45 which may have a cover 46 sealed by a gasket or solder or the like 47 to the box 45. An oil seal plug 48 may be provided to fill the box to an oil level 50 submerging all of the operating parts. The measuring finger 20 may have 55 a rod 51 passing through a side of the case through a sealed bearing, not shown, and be secured to a hub 52 on an arcuate segment 53 carrying a cam advancing operating lever 54 and a cam advancing retraction operating lever 55. A spring 57 is connected to the segment at an ear 58 and to the box at 59. The spring 57 biases the segment 53 to a stop 60 which limits the counterclockwise motion of the segment 53. In the position shown in Fig. 2

the segment is biased into engagement with a stop 61 for the reason that the measuring finger 20 is held down by the sheet 12 in turn held in position by the conveyor tapes 15.

It is to be noted in referring to Fig. 2 that a distance x is the effective moment arm of the spring 57 to rotate the segment 53. Referring to Fig. 4 it is seen that the distance y is greater than x . It is also to be noted that a tension spring 65 exerts greater force in the position shown in Fig. 2 than in the position shown in Fig. 4. 10 These spring forces may be so balanced with the variable moment arms x and y so that when the measuring finger is depressed as shown in Fig. 2 or retracted as shown in Fig. 4 there may be substantially a constant spring pull exerted upon the measuring finger 20. Inasmuch as there are a large number of these measuring fingers 20 extending up between the conveyor tapes 15 when in the retracted position it is important that a high spring force together with low inertia parts be maintained as nearly as possible. My novel spring arrangement in connection with the arcuate segment 53 and the operating levers 54 and 55 provides such relationship and hence permits of relatively high spring forces for relatively light parts.

With the device submerged in oil as shown and relatively high spring forces on the spring 65, it is possible to rotate the ratchet wheel 30 rapidly and still stop the same sharply in the two $\frac{1}{16}$ turn positions. It is noted in referring to Fig. 2 that the lever arm 55 has been rotated around its pivoting point 55A and has dropped off a point 68 of the ratchet 30. The spring 65 will thus rotate the lever 55 clockwise to cause it to strike a blow upon a surface 69 to contribute to quickly stopping the rotation of the ratchet 30. At substantially the same instant the lever 54 will engage a surface 70 also to contribute to the stopping motion.

Upon the other sense or movement of the measuring finger 20 in a counterclockwise direction, the lever 55 will rotate the ratchet 30 clockwise. In this instance, as shown in Fig. 4, the lever 54 drops off the surface 70 and the lever 55 engages the surface 69 to contribute to rapid stopping when the lever 20 rotates counterclockwise. It is to be understood that the switches 31, 38, 39 and 40 accordingly are provided a snap action by the motion in clockwise and counterclockwise direction of the measuring finger 20 and hence, it is not required that snap switches be used. However, it is to be understood that the broad concept of the invention also may use snap switches and such have actually been used in devices of this type.

Each of the switches 31, 38, 39 and 40 controls timers 80, 81, 82 and 83 in the timer box 22. Accordingly, a device is provided which can have four articles at a time in the folding machine and different of the timers respond to the measurement of the separate items and control the folding devices 25 and 26 for effecting the proper folds in the pieces. Inasmuch as all the devices are identical only one will be described in detail. With the contact 34 engaged by the switch blade 31, current will flow from line wire L1 to the switch contact 31, contact 34, wire 85 to timer 80; and through wires 86 and 87 to a motor 88 driving a free wheeled overrunning gear 89 to rotate a cam 90 in a clockwise direction. In addition, current passes through a wire 92 to a $\frac{1}{4}$ speed motor 93 driving a similar overrunning gear 94 to turn a cam 95 in a clockwise direction. With such structure, the cam 90 will rotate initially at a speed corresponding of half the speed and cam 95 will operate at $\frac{1}{4}$ speed of the conveyor tapes in the folding machine as long as the measuring finger 20 is in its depressed position thus engaging contact arm 31 with contact arm 34. Accordingly, the cams 90 and 95 will rotate to positions proportional to the $\frac{1}{2}$ length of the article being measured, the $\frac{1}{4}$ length of the article being measured in a manner more fully described in the above mentioned Kagan patent. Cams 90 and 95 will be rotated clockwise and switch

arms 97 and 98 will engage their respective contacts 99 and 100 to establish a holding circuit until they disengage after one complete revolution.

When the sheet 12 passes the measuring finger 20 it is moved by the spring 57 to the retracted position shown in Fig. 4 thus rotating the ratchet 30 $\frac{1}{16}$ turn in the clockwise direction and engaging a contact 101 with the contact arm 31. The contact 34 will be instantly broken so that the above traced circuits to motors 88 and 93 are broken. However, simultaneously therewith the following circuit is established from line wire L-1 through switch arm 31 a contact 101 wire 102 to the timer 80 through wire 103, wire 104, contact 99, switch arm 97, wire 105 to a full speed motor 106, wire 107 and wire 108 to line wire L-2. This circuit will energize motor 106 which through an overrunning gear 110 will drive the cam 90 at a speed corresponding to the full speed of the conveyor tapes in the folding machine 10.

A circuit for a full speed motor 111 may be traced from wire 103 under control of switch contact 101 through a wire 112 contact 100 switch arm 98 a wire 115 motor 111 a wire 116 and wire 108 to the line wire L-2.

On each of these circuits it is to be noted that the full speed motors 106 and 111 are in circuit with contacts 99 and 100 respectively. Hence, when the cams 90 and 95 make one complete revolution the switches 97 and 98 open the circuits to these motors to stop rotation of the cams.

When cams 90 and 95 complete a predetermined portion of their cycle, for example, they operate switches 120-121 and 122-123 to control the operation of the half and quarter folder mechanisms 25 and 26 respectively through circuits now to be described.

When the switch blade 121 engages the contact 120 the article to be folded will be so positioned in the folding machine that when the folding device 25 moves the folding blade 23 to the folding rolls cooperable therewith substantially the exact center point of the article measured will be forced between these rolls. Such action of the control motor is accomplished through the following circuit. From line wire L-1 wires 125 and 126 to control motor 25 through wire 127 and 128 to the control box 80, wire 129, contact 120, switch blade 121, wire 130 and wire 108 to line wire L-2. Hence, as the dwell in the cam 90 passes a roller 131 connected with the switch blade 121 the above described circuit is established to cause actuation of the $\frac{1}{2}$ folding operator motor 25.

When the article to be folded controlled by the folding control 80 is in position adjacent the $\frac{1}{4}$ fold blade 24 the dwell in cam 95 will be so positioned adjacent a roller 133 to cause engagement of switch blade 123 with contact 122 to establish the following circuit from line wire L-1 through wire 125, wire 135, folder operator 26, wire 136, wire 137 to folder control 80, wire 138, contact 122, switch blade 123, wire 140 and wire 108 to line wire L-2. This circuit will cause actuation of the $\frac{1}{4}$ fold device.

Measuring finger operated cams 35, 36 and 37 cooperate respectively and in succession with switch arms 38, 39 and 40. The contact arm 38 cooperates with contacts 150 wires 151 and timing mechanism 81 to cause a similar operation to that described above on the next following article to be folded by the folding machine 10. Likewise, contact arms 39 and 40 cooperate with contacts and timing mechanisms 82 and 83 respectively to operate on following articles. After the cam 37 has controlled an operation the cam 33 will next be brought into play to control the folding of the next following article.

In the foregoing description it is seen that I have provided a novel and accurate folder control mechanism to more accurately provide folding operations at high speeds. Inasmuch as alterations and modifications will occur to those skilled in the art in view of this disclosure it is to be understood that I am not to be limited in my

invention only to the specific forms shown and described but by the scope of the following claims.

I claim:

1. In a folding machine having conveyor means for carrying articles to be folded along a path and folding means for said articles, the combination of a plurality of timing means having first and second characteristic manners of operation, each of said timing means being adapted to cause operation of said folding means when operating in said second characteristic manner, measuring means operable by movement of an article along said path and having a first position when sensing said article and a second position when not sensing said article, control means directly connected to and rotatably moved one step by said measuring means when in said first position and a second step in the same direction when in said second position, and selector means moved by said control means for controlling the operations of said several timing means respectively in said first characteristic manner when said measuring means is in its first position and controlling the second characteristic operations of said timing means when said measuring means is in said second position.

2. In a folding machine having conveyor means for carrying articles to be folded along a path and folding means for said articles, the combination of a plurality of timing means each operable in a first characteristic manner at a first time and in a second characteristic manner at a second time, each of said timing means being adapted to control the operation of said folding means when operating in said second characteristic manner, measuring means sensitive to movement of an article along said path and having a first position when sensing said article and a second position when not sensing said article, control means including a ratchet wheel moved by said measuring means when in said first position to a first position for causing operation sequentially of said timing means in said first characteristic manner, said control means being moved to a second position by said measuring means when it is in its second position, and selector means moved by said control means for selecting the timing means to be operated and also controlling the second characteristic operation of the timing means being operated when said measuring means moves to said second position.

3. In a folding machine control having means for carrying an article to be folded along a path, the com-

bination including measuring means responsive to the passage of an article past a predetermined point, said measuring means being movable in one sense when the leading edge of an article reaches said point and in the opposite sense when the trailing edge of said article passes said point, said means including a pair of operating levers, selector means including a ratchet wheel co-operable with said levers and operable thereby, and spring means connecting said levers and biasing each of said levers into contact with said ratchet wheel to act as ratchet pawls, said spring means being located relative to each other so that the combined force exerted is substantially uniform, said wheel being moved in predetermined steps by said levers in one direction by said measuring means upon each movement of said measuring means.

4. In a folding machine control having means for carrying an article to be folded along a path, the combination including measuring means responsive to the passage of an article past a predetermined point, said measuring means being movable in one sense when the leading edge of an article reaches said point and biased for movement in the opposite sense when the trailing edge of said article passes said point, a ratchet wheel, oscillatable means connected with and movable by said measuring means, a pair of operating levers contactable with said ratchet wheel for driving the same, said levers being connected to said oscillatable means, said operating levers being located either side of the axis of oscillation of said oscillatable means, spring means biasing said levers into engagement against said ratchet wheel, spring means urging said oscillatable means in one direction, said spring means being located to provide a predetermined substantially uniform force thereto regardless of the position of said measuring means, and selector means moved in predetermined steps in one direction by said measuring means regardless of the sense of movement of said measuring means.
